R. T. BELL,

LID SUPPORTER.

APPLICATION FILED JAN. 3, 1921

1,390,751.

Patented Sept. 13, 1921.

Inventor
Raymond T. Bell
J. Gochum Jr.
Atty.

UNITED STATES PATENT OFFICE.

RAYMOND T. BELL, OF CHICAGO, ILLINOIS, ASSIGNOR, BY MESNE ASSIGNMENTS, TO JEWETT PHONOGRAPH COMPANY, A CORPORATION OF MICHIGAN.

LID-SUPPORTER.

1,390,751.

Specification of Letters Patent. Patented Sept. 13, 1921.

Application filed January 3, 1921. Serial No. 434,499.

To all whom it may concern:

Be it known that I, RAYMOND T. BELL, a citizen of the United States, residing at Chicago, in the county of Cook and State 5 of Illinois, have invented certain new and useful Improvements in Lid-Supporters, of which the following is a specification.

This invention relates to improvements in lid supporters, particularly adapted, 10 though not necessarily limited in its use with the lid or cover of sound reproducing machine cabinets, and one of the objects of the invention is to provide an improved device of this character which will support or 15 maintain the lid or cover at any degree of elevation or angle and which will be automatic in operation, but which will yield under pressure to permit the cover or lid to be raised or lowered at will.

20 A further object is to provide an improved device of this character which will be of a unitary structure whereby the device may be readily and properly placed in position.

A further object is to provide an improved 25 device of this character embodying a controlling spring, and improved means whereby the tension of the spring may be varied at will without the necessity of disconnecting any of the parts of the device.

30 To the attainment of these ends and the accomplishment of other new and useful objects as will appear, the invention consists in the features of novelty in substantially the construction, combination and arrangement 35 of the several parts, hereinafter more fully described and claimed and shown in the accompanying drawing illustrating this invention and in which—

Figure 1 is a side elevation showing the 40 lid supporter applied to a sound reproducing machine cabinet, the cabinet being in sections and with the lid partly raised.

Fig. 2 is a view similar to Fig. 1 showing the parts in another position.

45 Fig. 3 is a detail sectional view on line 3—3, Fig. 2.

Referring more particularly to the drawing the numeral 10, designates a cabinet having the usual lid 11, hinged thereto as at 12.

50 Connected with the cabinet in any suitable manner is a base 13, of any desired size and configuration. A lever like element 14, is pivotally connected as at 15, by one end, to the base 13, and pivotally connected to the 55 other end of the element 14, as at 16, and

by one end thereof is a link 17. The other end of this link 17, is pivotally connected as at 18, to a bracket or anchoring device 19, which latter is in turn secured to the lid 11, so that when the lid 11, is moved about its pivot or hinge 12, the link 17, and the element 14, will both be moved about their respective pivots.

Slidably mounted upon the element 14, is another element 20, which is provided with 60 an elongated slot 21, in its body. The element 14, is provided with a threaded opening 22, shown more clearly in Fig. 3, adapted to receive the end of a screw or bolt 23, which latter passes through a slot 65 21, in the element 20, so that the head 24, will operate upon the element 20, to cause a binding action between the element 20, and the element 14. If desired a washer 25, and a locking device 26, may be interposed between the head 24, of the bolt 23, and the element 20.

This element 20, is provided with depending flanges or ears 27, which overhang the 70 edges of the lever like element 14, so as to permit the element 20, to be freely adjusted upon the element 14, when the bolt 23, is loosened and will coöperate with the sides of the element 14, to prevent a rotary or 75 pivotal movement in a lateral direction being imparted to the element 20, when a strain is exerted upon the element.

A spring 28, is anchored or connected at one of its ends 29, with the base 13, and is connected at its other end 30, preferably to an ear or projection 31, on the element 20, and preferably through the medium of an intermediate link 32, one end of which link is connected with a spring and the other end with the element 20.

With this improved construction it will be manifest that the device being of a unitary construction it may be readily placed into a cabinet in any desired position and by adjusting the element 20, with reference to the 80 element 14, the tension of the spring 28, may be varied.

The element 20, is adapted to be reversed with respect to the element 14, that is to say the bolt 23, may be removed and the element 20, turned end for end on the element 14, so that instead of having the projection or point to which the end of the spring 28, is secured to the element 20, adjacent the pivot 16, of the element 14, and link 17, the 100 105 110

element 20, may be so positioned that the point of connection of the spring therewith may be disposed adjacent the pivot 15, and thereby increase the range of adjustment of the tension of the spring 28.

If desired, any suitable means may be provided for creating a friction at the pivot 15, such for instance as the means shown and described in the patent to Bell and Mandel, 10 1359953, issued November 23, 1920.

While the preferred form of the invention has been herein shown and described it is obvious that many changes may be made in the details of construction, within the scope 15 of the claims, without departing from the spirit of this invention.

What is claimed as new is:—

1. A lid supporter embodying a base 20 adapted to be secured to a fixed support, an element pivotally connected with the base, a link pivotally connected by one end with the said element and by its other end with the lid whereby when the lid is moved the elements will be moved about their pivots, 25 a spring connected at one end to a fixed support, and an element adjustably carried by the first recited element and to which second recited element the other end of the said spring is connected.

2. A lid supporter embodying a base 30 adapted to be secured to a fixed support, an element pivotally connected with the base, a link pivotally connected by one end with the said element and by its other end with the lid whereby when the lid is moved the elements will be moved about their pivots, 35 a spring connected at one end to a fixed support, and an element mounted upon the first recited element intermediate the pivots thereof and to which second recited element the other end of the said spring is connected.

3. A lid supporter embodying a base 45 adapted to be secured to a fixed support, an element pivotally connected with the base, a link pivotally connected by one end with the said element and by its other end with the lid whereby when the lid is moved the elements will be moved about their pivots, 50 a spring connected at one end to a fixed support, and an adjustable and reversible element mounted upon the first recited element intermediate the pivots thereof and to which second recited element the other end of the said spring is connected.

4. A lid supporter embodying an element 55 pivotally connected at one of its ends to a fixed support, a link pivotally connected by one of its ends to the other end of the said element and by its other end to the lid, an 60 element adjustably mounted upon the first recited element, and a spring connected at one of its ends to the second recited element and at its other end to a fixed support.

5. A lid supporter embodying an element 65 pivotally connected at one of its ends to a

fixed support, a link pivotally connected by one of its ends to the other end of the said element and by its other end to the lid, an element adjustably mounted upon the first recited element, a link connected with the second 70 recited element, and a spring connected at one end with the second recited link and at its other end to a fixed support.

6. A lid supporter embodying an element pivotally connected at one of its ends to a 75 fixed support, a link pivotally connected at one of its ends with the other end of the said element and at its other end to a lid, an element slidably mounted upon the first recited element, means for securing the second recited element against adjustment with respect to the first recited element, means for maintaining the second recited element against rotative adjustment with respect to the first said element, and a spring connected 85 at one of its ends with the second recited element and the other end to a fixed support.

7. A lid supporter embodying an element pivotally connected at one of its ends to a fixed support, a link pivotally connected at 90 one of its ends with the other end of the said element and at its other end to a lid, an element slidably mounted upon the first recited element, one of said elements being provided with an elongated slot, a fastening device 95 connected with the other element and extending into the slot, one or more ears or projections connected with one of the said elements and coöperating with the other element for maintaining the adjustable element against 100 turning about the said fastening device, and a spring connected at one of its ends with the said adjustable element and at its other end with a fixed support.

8. A lid supporter embodying a pivotally mounted element, a second element carried thereby and secured for adjustment with relation thereto, and a spring connected at one of its ends with the said second element and at its other end to a fixed support. 105

9. A lid supporter embodying a pivotally mounted element, a second element carried thereby and secured for adjustment with relation thereto, and a spring connected at one of its ends with the said second element and at its other end to a fixed support, the said second element being adapted to be reversed with respect to the first recited element. 110

10. A lid supporter embodying a pivotally mounted element, a second element carried thereby and secured for adjustment thereupon, one or more ears connected with one of the said elements and overhanging the other of the said elements, and a spring connected at one of its ends with the said second element and at its other end with a fixed support. 120

11. A lid supporter embodying a pivotally mounted lever like element, a second element slidably mounted thereupon, one of 130

the elements having an elongated slot therein, a fastening device for securing the elements against relative adjustment, said fastening device being connected with one of 5 the elements and extending into the said slot, a projection extending from one of the elements and engaging a portion of the other element for maintaining the said second element against rotative movement with respect 10 to the other element, and a spring connected at one of its ends to the said second element and at its other end to a fixed support.

12. A lid supporter embodying a pivotally mounted lever like element, a second element 15 slidably mounted thereupon, one of

the elements having an elongated slot therein, ears projecting from one of the elements and overhanging the other of the elements, a fastening device passing through the said slot and engaging the other of the elements 20 for securing the said second element against adjustment with respect to the first recited element, and a spring connected at one end with the said second element and at its other end to a fixed support. 25

In testimony whereof I have signed my name to this specification, on this 29th day of December, A. D. 1920.

RAYMOND T. BELL.
